UNITED STATES PATENT OFFICE.

HENRY P. CLAUSEN, OF MOUNT VERNON, NEW YORK, ASSIGNOR, BY MESNE ASSIGNMENTS, TO WESTERN ELECTRIC COMPANY, INCORPORATED, A CORPORATION OF NEW YORK.

CIRCUIT-CONTROLLING DEVICE.

1,243,261.

Specification of Letters Patent. Patented Oct. 16, 1917.

Application filed October 8, 1915. Serial No. 54,790.

To all whom it may concern:

Be it known that I, HENRY P. CLAUSEN, a citizen of the United States, residing at Mount Vernon, in the county of Westchester and State of New York, have invented certain new and useful Improvements in Circuit-Controlling Devices, of which the following is a full, clear, concise, and exact description.

10 This invention relates to circuit controlling devices, and more particularly to a thermal circuit controlling device and its application to a circuit.

This invention has for its object the production of an improved form of thermal relay and the application thereof to an electrical circuit, with means for producing an opening or closing of a circuit, whereby heat produced in one thermal circuit causes 20 a contact to close, and heat produced in a second thermal circuit causes the contact to open.

In accordance with the features of this invention, there is provided a thermal device 25 comprising two heat expansible members, each having a current carrying thermal coil and governing the operation of a contact controlling means. The heat expansible members and their circuits are so combined 30 that the operation in either direction of the contact controlling means may be influenced by the action of heat generated in the thermal coils.

In the drawing, Figure 1 is a circuit diagram illustrating one embodiment of this invention; and Fig. 2 is a circuit diagram illustrating an application of this invention to a telegraph system for the purpose of rendering a normally disabled receiving means, 40 controllable over a telegraph line circuit, to be operatively included with the line circuit. In each of the figures similar characters of reference are employed to indicate similar parts.

45 Considering first the characteristic form of this thermal relay. One end of an expansible member 11 is fixed to a supporting base 10, and at its other end carries a transverse member 12. One end of a second expansible member 13 is fixed to the member 12 to form a parallelism with the first expansible member 11. The free end of the member 13 is adapted to engage a contact spring 14 and by pressure, or the absence 50 of pressure thereon, act to control the oper-

ation of the contacts 15 and 18. Thermal coils 16 and 17 are provided for the expansible members 11 and 13, respectively. The contacts 15 are employed in the control of the thermal coil circuits, and contacts 18 55 may be employed to control other circuits.

When the thermal relay is in the normal position, which corresponds with the position shown in the drawing, no current action is present in its circuits; therefore, a 60 uniform temperature is present in each of the expansible members 11 and 13. Under this condition the expansible member 13 does not exert pressure on the contact spring 14, and the contacts 15 and 18 accordingly 70 remain open.

In describing the operations which take place when current action is present in the thermal circuits, let it be assumed that a key 23 is depressed. Current from battery 75 19 will now traverse a series circuit formed through the thermal windings 16 and 17 in which the thermal coil 17 is proportioned to generate heat more rapidly than the thermal coil 16. This results in the member 13 80 being expanded to exceed the expansion of the member 11, and the spring 14 is, therefore, depressed by the member 13 to close the contacts 15 and 18. Closure of the contacts 15 establishes the conductor 25 in shunt 85 on the thermal coil 17 thereby causing cessation of current in this coil. This change of circuit relation renders the terminals of the thermal coil 16 subject to the full potential of the battery 19. The resulting 90 increase of current flow through the coil 16 causes the expansible member 11 to expand and move the member 13 to relieve the pressure on the spring 14, thereby permitting the contacts 15 and 18 to open. It will be 95 noted that at the instant closure of the contacts 15 takes place, the expansible member 13 is released to contract and this movement is accordingly accumulative with the expanding movement of the member 11 in relieving the pressure exerted by the member 13 on the contact spring 14.

By retaining the key 18 closed it will be noted that continuous automatic reciprocating movement of the working parts of this 105 relay will take place.

In Fig. 2 is indicated diagrammatically a telegraph system in which a modified embodiment of a thermal relay, such as referred to herein, is employed in a manner 110

suitable for practising the features of this invention. The numerals 1, 2 and 3 indicate three separate telegraph stations connected in series with a main line conductor 4, line batteries 5 and 6 and the earth connections. At stations 1 and 3, all of the telegraph equipment is of well-known type, while at station 2, in addition to the usual telegraph devices, a thermal relay 9 and a key 24 is employed in accordance with this invention.

Considering first the conditions which are present when the circuits are in the normal position as shown in the drawing, Contacts 15 8 of a main line relay 7 retain a circuit from a battery 19 through the thermal coil 16 carried by the expandible member 11. The member 11 is thereby expanded longitudinally to move the member 13 from engagement with the spring 14, in which position the contacts 15 remain open and accordingly disable a telegraph sounder 26. Although the line relay 7 responds when messages are transmitted between stations 1 and 25 3, thereby causing momentary interruptions of current in the thermal coil 16, these interruptions are comparatively short and therefore do not permit the expandible member 11 to contract sufficiently to close the contacts 15. Premature inclusion of the sounder 26 with the line circuit is, therefore, prevented by the inertia of the thermal relay.

In describing the operations necessary in selecting and communicating with station 2, let it be assumed that station 1 desires to establish such a connection. At station 1 a key-closing switch 28 is moved to the open position, thereby interrupting a shunt path 40 around an associated telegraph key 27 to cause a cessation of current on the main line conductor 4. Upon the circuit being retained in this position for a predetermined period, the following operations take place 45 automatically at station 2. Line relay 7 is deenergized to open its contacts 8, thereby excluding the thermal coil 16 of the thermal relay 9 from the battery 19. The expandible member 11 now contracts and causes the member 13 to depress the spring 14 to close the contacts 15. Closure of the contacts 15 prepares a series circuit formed through the sounder 26 and a second thermal winding 17 of the thermal relay 9. Now, upon the operation of key 27 at station 1, as in transmitting a message, the line relay 7 responds, and, through its contacts 8, includes the sounder 26 and the thermal coil 17 in series with the battery 19. It will be noted that 55 each closure of the line relay contacts 8 permits current from the battery 19 to traverse the windings 16 and 17 of the thermal relay. The amount of heat generated by the winding 17, however, is in excess of the heat 60 generated in the winding 16. Therefore, the

expansion of member 13 is in excess of the expansion of member 11. Accordingly the closed position of the contacts 15 are not disturbed, and the sounder 26 continues responsive to the line relay 7. 70

At the conclusion of a communication, the sounder 26 may again be disabled by depressing the key 24 to open the circuit of the thermal winding 17 for a period sufficient to permit the expansion of the member 11, in response to current present in the thermal coil 16, to open the contacts 15. 75

The sounder 26 may also be rendered effective from station 2 by opening the key-closing switch 28 as described for station 1. 80

What is claimed is:

1. A circuit controlling device comprising two expandible members mechanically connected, a heat generating element for each expandible member, one element having greater heat generating capacity than the other, and contact members controlled by the joint action of said expandible members. 85

2. A circuit controlling device comprising a base, an expandible member supported thereby, a second expandible member connected to the first expandible member, a heat generating element for each expandible member, one element having greater heat generating capacity than the other, whereby the expansion of one member is greater than that of the other member, and a switching member operated in one direction by the simultaneous expansion of both 90 of said expandible members and in another direction by the individual expansion of one of said expandible members. 100

3. A circuit controlling device comprising a base, an expandible member mounted on said base, a second expandible member supported by said first expandible member in parallel relation thereto, circuit controlling contacts, a heat generating element for the first of said members to cause the 105 expansion thereof and thereby to open said circuit controlling contacts, and a second heat generating element of lesser capacity for the second of said members to cause the expansion thereof and thereby to close said 110 circuit controlling contacts. 115

4. A circuit controlling device comprising a base, an expandible member mounted on said base, a second expandible member supported by said first member, circuit controlling contacts, a heat generating element for the first of said members to cause the expansion thereof and thereby to open said contacts, and a second heat generating element for the second of said members to cause the expansion thereof and by coöperative operation thereof with the first of said members to close said contacts. 120 125

5. A circuit controlling device comprising a base, an expandible member mounted 130

- on said base, a second expansible member supported by said first member, a heat generating element for each member for causing the expansion thereof, and circuit controlling contacts arranged to be closed by the coöperative expansion of both members and to be opened upon the individual expansion of the first member. 5
6. A circuit controlling device comprising a base, an expansible member mounted on said base, a second expansible member supported by said first member, a plurality of contact springs, a heat generating element for the first of said members to cause the expansion thereof, a second heat generating element of lesser capacity for the second of said members to cause the expansion thereof and by operating coöperatively and reciprocally with said first element to control the actuation of said contact springs. 20
7. A circuit controlling device comprising a base, an expansible member mounted on said base, a second expansible member supported by said first member, circuit controlling contact springs, and coöperatively operating heat generating elements having different capacities for said expansible members to produce unequal expansion of said members thereby actuating said circuit controlling contact springs. 25
- 30

In witness whereof, I hereunto subscribe my name this 5th day of October A. D., 1915.

HENRY P. CLAUSEN.
